US0D1065150S

(12) **United States Design Patent** (10) Patent No.: **US D1,065,150 S**
(45) Date of Patent: ** Mar. 4, 2025

(54) **LOUDSPEAKER**

(71) Applicant: **Harman International Industries, Incorporated**, Northridge, CA (US)

(72) Inventors: **Jonas Ceppa**, Shenzhen (CN); **Dario Distefano**, Shenzhen (CN)

(73) Assignee: **Harman International Industries, Incorporated**, Northridge, CA (US)

(**) Term: **15 Years**

(21) Appl. No.: **29/878,389**

(22) Filed: **Jun. 21, 2023**

(51) LOC (15) Cl. **14-01**

(52) U.S. Cl.

(57) **CLAIM**

The ornamental design for a loudspeaker, as shown and described.

DESCRIPTION

FIG. 1 is a top, front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The evenly spaced broken lines in the figures are included for the purpose of illustrating portions of the loudspeaker that form no part of the claimed design. The dash-dot broken lines in the figures represent the boundaries of the claimed design and form no part of the claimed design.

1 Claim, 7 Drawing Sheets
